UNITED STATES PATENT OFFICE.

ALBERT L. OVERHOLT, OF MINNEAPOLIS, MINNESOTA, ASSIGNEE, BY MESNE ASSIGNMENTS, TO STEINER SALES COMPANY, OF SALT LAKE CITY, UTAH, A CORPORATION OF UTAH.

TOWEL HOLDER.

Application filed April 1, 1922. Serial No. 548,846.

This invention relates to means in towel holders adapted to feed a web of toweling and more particularly relates to towel cabinets having a roll of toweling mounted 5 therein and adapted to measure and to limit the delivery or feed of the clean portion of the toweling with each pull of the user thereon. More specifically this invention relates to means for locking the feed-limiting mechanism of such cabinets in feed-limiting position.

The object therefore of this invention is to provide an improved towel holder.

Other objects of the invention will more 15 fully appear from the following description and the accompanying drawings and will be pointed out in the annexed claims.

In the accompanying drawings, there has been disclosed a structure designed to carry 20 out the objects of the invention, but it is to be understood that the invention is not confined to the exact features shown as various changes may be made within the scope of the claims which follow.

25 In the accompanying drawings forming part of this specification:

Figure 1 is a vertical sectional view through a towel cabinet showing the invention as applied to a reel type of measuring 30 device;

Figure 2 is a fragmentary similar view with the reel in locked position;

Figure 3 is a fragmentary cross-sectional view on the line 3—3 of Figure 2;

35 Figure 4 is a vertical sectional view through a portion of a cabinet showing the invention as applied to a cylinder type of measuring device;

Figure 5 is a view similar to Figure 4 40 showing the measuring cylinder in locked position;

Figure 6 is a vertical sectional view of a cabinet showing a modified form of locking means applied to a cylinder type of measuring 45 device;

Figure 7 is a partial vertical sectional view of an apparatus similar to that shown in Figure 6; but with the locking means in cylinder locking position;

50 Figure 8 is a view in plan of the apparatus shown in Figures 6 and 7 but with the portion of the casing broken away;

Figure 9 is a sectional view on the line 9—9 of Figure 7;

Figure 10 is a vertical sectional view 55 through a cabinet showing an, oscillatory type of measuring apparatus.

Figure 11 is a view similar to that of Figure 10 but with the measuring bar in locked position;

Figure 12 is a cross-sectional view on the line 12—12 of Figure 11; and

Figure 13 is a view in front elevation of the cabinet shown in Figures 10, 11 and 12.

Referring to the embodiment of the invention shown in Figures 1 to 3 inclusive, there is provided a cabinet somewhat similar to that shown in the pending application of the inventor hereof, Serial Number 484,843, filed July 15, 1921. The cabinet includes a top 70

13 and a tilting member 14 having a compartment 15 within which a roll 16 of clean toweling is adapted to be placed and to rest upon the base thereof. This compartment is adapted to slide upon horizontal guides 17. 75 The member 14 is provided with a latch device 18 by means of which the adjacent depending edge of the top 13 may be engaged and the member 14 thereby releasably locked in place. The angled plate 19 forms a stop 80

against which the flanged lower edge of the member 14 is seated. The towel compartment has a rear wall 21 over which the loose end of the towel is fed. The compartment is

preferably of such dimension that its rear 85 wall 21 is spaced from the rear wall 22 of the cabinet and an arcuate spring 23 is riveted at its upper end to the rear wall of the cabinet and downwardly extends so that its

middle bowed portion is adapted yieldingly 90 to hold the toweling web against the adjacent face of the rear wall 21 of the compartment. The towel web is thus placed under a frictional resistance to feeding.

Means are mounted within the cabinet to 95 grip the towel upon feeding movement thereof whereby the feed is limited. Such a gripping means may be provided by a reel comprising a hub 24 having a weight 25 and plates 26 and 27 arranged in cross relation

100 on the hub and projecting outwardly therefrom and adapted to have their ends contact with the loose end of the towel. The hub 24 may conveniently be mounted upon any shaft rotably borne by opposed brackets

105 20 riveted to the opposite sides of the casing. The plate 27 is of greater length than the plate 26 and normally holds the towel

in the position shown in Figure 1, the weight 25 being on the under side of the hub and tending to hold the plate 27 in its raised position. A bar 28 is mounted transversely 5 of the cabinet below the reel and spaced therefrom so that only a longer arm of the plate 27 may contact therewith upon revolution of the reel. As is shown in Figure 1, the web of toweling, upon installation of a 10 roll, passes around the reel in engagement with its plate ends and then rearwardly passes about the bar 28. When pull is applied to the loose end of the toweling, the reel will be revolved upon its axis against the 15 gravitational tension of its weight 25. The plate 26 will pass the bar stop without contacting therewith, but the longer plate 27 will contact with the bar and clamp a portion of the toweling between it and the stop as 20 is shown in Figure 2. Further feeding of the toweling is thereby fixedly prevented even though the pull be continued. When the loose end of the toweling is released by the user, the hub weight 25 causes the reel to be reset 25 or returned to its normal position with the plate 27 out of such feed-limiting position. The end of the plate 27 will slide on the toweling without raising that portion of the toweling which has been withdrawn from the 30 cabinet. The amount of clean toweling delivered will depend upon the lineal distance traveled by the end of the longer arm of the plate 27 before it clamps the toweling against the stop 28. The measure of each toweling 35 feeding may be obviously predetermined by the construction and dimensions of the parts.

In this improved cabinet, means are provided to retain the toweling gripping means in its feed-limiting position. Such means are 40 preferably releasable to permit the toweling gripping device to reset itself automatically, that is, to return to normal non-limiting position. Such retaining means is shown in Figures 1, 2 and 3 as formed by a pivoted 45 member normally projecting in the path of one of the reel plates. This member comprises a lever 29 pivotally mounted upon a stud 31 secured to the side wall 32 of the cabinet. The forward end of the lever 29 is provided with a pin 33 projecting through 50 an elongated slot 34 formed in the side wall 32. The arm of the lever on the other side of its pivotal mounting is offset to provide a latching hook 35. Preferably the hooked 55 end of the lever is of greater weight than the handle portion thereof, so that the hook 35 normally is held in the position shown in Figure 1 wherein the hook remains in the path of the plate 26. Upon downward pull 60 of the loose end of the toweling, the reel will be moved to the position shown in Figure 2, whereat one end of the plate 26 has passed the hook and the short arm of the plate 27 has come to a stop with the hook descended 65 over the rearward face thereof so as to hold

the reel against reversing movement under influence of the hub weight 25. The toweling gripping means is thus retained in locked feed-limiting position. This locking means is releasable by subsequent depression of the pin 33 so that the reel may automatically reset itself. Upon such resetting or return to normal position, the apparatus is ready for another downward pull whereby a predetermined measure of clean toweling is delivered. Preferably the edge portion 36 of the plate 26 adjacent the latch is cut away as shown in Figure 3. The purpose of this is to avoid engagement of the plate 26 with the hook 35 either in its movement in the feeding direction or in the resetting direction. 75

In the different form of toweling feeding mechanism shown in Figures 4 and 5, the same pivoted latch may be employed. 80 Therein, instead of the reel structure, there is shown a cylinder 37 rotatably mounted in the side walls of the cabinet and having a similar weight 25 secured to the inner face of the cylinder. Preferably this cylinder is made of sheet metal so that a transverse flange 38 may be conveniently cut therefrom and radially outwardly projecting in order to serve a function similar to that of the longer arm of the plate 27 in 85 the reel device above mentioned. The weight 25 normally causes the cylinder 37 to assume the position shown in Figure 4, with the flange 38 on the forward upper side of the cylinder. The loose end of the toweling, after passing the rounded edge 39 of the compartment 15 rests upon the edge of the flange 38 so that when a pull is exerted on the lower loose end of the toweling, the cylinder 37 will be rotated on its axis until the flange 38 is moved adjacent the bar 28 as shown in Figure 5. In such position, the flange 38 clamps the toweling between the bar and the surface of the flange with the result that the harder the pull upon the toweling, the more firmly will the toweling be gripped and it will not be possible to withdraw any more of the clean toweling from the cabinet at least until the loose end has been released, whereupon the weight 25 tends to reset or return the cylinder to its 90 normal position. Then the user can obtain another length of toweling by downward pull upon the loose end of the toweling. A retaining means similar to that shown in 95 Figures 1 to 3 inclusive, may be employed in conjunction with this cylinder type to lock the cylinder in feed-limiting position. The lever 29 is similarly pivotally mounted and its hooked portion 35, as shown in Figure 4, normally rests against the cylinder periphery and, upon feeding movement of the cylinder, may drop into the slot 41 cut in the cylinder periphery. The slot 41 and the flange 38 are formed in a spaced relation. 100

105

110

115

120

125

130

tion such that when the flange 38 is in towel-clamping position, the hook 35 will have dropped within the slot 41 and prevent reversed releasing movement of the cylinder, as is shown in Figure 5. Upon depression of the pin 33, the hook 35 will be moved from the locking slot 41 and the weight 25 will automatically reset the cylinder 37 without raising the free end of the toweling.

In the form of cabinet shown in Figures 6 to 9 inclusive, there is provided a casing having a top 13, back wall 22, base 42, and front wall 43. The front wall is preferably cut away to permit removal and insertion of the roll of clean toweling. The opening thus formed may be closed by a door 44 secured to the front wall 43 in any convenient manner. In this construction the toweling end is fed from the roll upwardly over a rod 45 and then downwardly over a second rod 46. These rods extend across the cabinet and are terminally mounted in the side walls 47 and 48 of the cabinet. The toweling, after passing over the rod 46, is passed around the end of the shelf 49 upon which the towel roll rests. This shelf 49 is preferably metallic, is supported by the side walls of the casing and has its rear end downwardly turned upon itself to form a bearing surface 51 for the towel thereafter passing about the periphery of the cylinder 37 and thence downwardly through a slot 52 cut in the base 42 of the cabinet. The rods 45 and 46 and shelf edge place the toweling under some frictional resistance. This cylinder is similar to that shown in Figure 4 while the bar 53, unlike the above-mentioned bar 28, is secured to the inner face of the front wall 43 of the cabinet. The cylinder flange 38 similarly clamps the feeding toweling against this bar 53 to limit the feed to a predetermined amount. In this embodiment of the invention the means to retain the flange in gripping position is provided by a lever 54 having an upper terminal hook 55 adapted to engage and retain the flange 38 in the same manner. The lever 54 is preferably L-shaped and is provided with a terminal button 56 upon its arm which projects forwardly through an elongated slot in the front wall 43 of the casing. The latching lever is mounted upon a pivot pin 57 carried by an upstanding bracket 58 riveted to the base 42 of the cabinet. Tension means, in the form of a compression spring 59, is provided yieldably to maintain the lever hook in the path of the flange 38 of the cylinder 37.

In the form of the invention shown in Figures 10 to 12 inclusive, the cabinet is shown as having a top 13, base 42, rear wall 22 and side walls 47 and 48. The front wall 43, similarly to that of the pre-

ceding cabinet form is cut away to provide an opening for replenishment of the towel roll. Such opening is closed by a similar door 44 having a latch 18 whereby the door may be released and downwardly turned upon its hinges 61 to open position. In this form the roll 16 of the clean toweling rests upon the base 42 of the cabinet and the loose end of the towel is forwardly and upwardly passed over a resistance bar 62 transversely extending across the cabinet and thence downwardly through the transverse slot 63 in the base 42. The feed-limiting mechanism is provided by an oscillatory member herein shown as U-shaped. The opposed forwardly extending legs 64 thereof are terminally outwardly offset and pivotally mounted in apertured brackets 65 riveted to the front wall 43. This U-shaped member also provides an integral transverse rod 66 preferably covered by a sleeve 67 preferably of a rubber composition. This rod is normally yieldably held in the position shown in Figure 10, against the detent 68 provided by an angled bracket secured to the side wall 48, by means of the tension springs 69 secured to the legs 64 and to small brackets 71 secured to the top 13. Upon installation of a roll 16, the end of the toweling is passed over and to the rear of the rod 66 so that, upon exertion of a downward pull of the loose towel end, the rod will downwardly travel with the toweling to the gripping position shown in Figure 11 whereat the towel is clamped by the sleeved rod 66 against the base 42 adjacent the slot 63 and thereby held against further feeding until after release of the loose end. In this form, the means for retaining such gripping means in feed-limiting position is provided by a lever 72 pivotally mounted upon the pin 73 carried by a bracket 70 secured to the side wall 48 and connected by a rod 74 forwardly extending therefrom and slidably projecting through the front wall 43 and terminally provided with an operating button 75 by which the rod may be outwardly pulled. The rod 74 has a collar 76 pinned thereto. A compression spring 77 is coiled about the rod and held between the collar 76 and the rear face of the wall 43 so that the rod is normally held in the rearward position shown whereby the offset arm 78 of the lever 72 is normally projected within the path of the sleeved rod. Upon downward travel of the sleeved rod, the arm 78 may yieldably move to permit the rod to travel therewith. Upon passage of the rod, the arm 78 tensionably returns to the locking position shown in Figures 11 and 12 whereby the sleeved rod is retained in feed-limiting position. A pull upon the button 75 swings the arm 78 from locking position and permits the automatic resetting of the sleeved rod for further feed.

upon a pull upon the loose end of the toweling.

I claim as my invention:

1. In combination with a towel holder and deliverer from which predetermined lengths of towel may be pulled without severing the same, of means operated by pulling out the towel to automatically grip and stop the delivery of the towel when the predetermined amount of towel has been pulled from the deliverer and to automatically reset itself to repeat the operation when the towel is released, said gripping means including a stationary element and an element movable with the towel, and mechanism for automatically locking said gripping means in gripping position, the said mechanism being provided with means for releasing the same when desired.
2. The combination, with a towel cabinet, means having a surface over which the loose end of the towel slides, and a rotating member having a flange for gripping the towel against said surface, the loose end of the towel resting on said rotating member and pull on said end increasing the pressure of said flange on the towel, and mechanism for automatically locking said gripping flange in gripping position, the said mechanism being provided with means for releasing the same when desired.
3. A towel holder comprising means for holding a web of towel so that portions may be fed off by pulling on the towel in a certain direction, and means for automatically gripping the towel as it is fed in the same direction, said gripping means preventing the further feed thereof when a predetermined length of towel has been delivered until said gripping means is re-set, said gripping means including a stationary member and an oscillating member, substan-

tially as described, and mechanism for automatically locking said gripping means in gripping position, the said mechanism being provided with means for releasing the same when desired.

4. A towel cabinet comprising a casing, a web of clean toweling supported therein, a feed controlled device including a stationary member and an oscillatable member effective to clamp the towel against the stationary member, said member being mounted for contact with the towel web, and actuated by the engagement of the towel web therewith for measuring a predetermined length of the towel and positively checking the feed when such length has been delivered, said oscillatable member being mounted to return to its normal position when the pull upon the towel ceases, and mechanism for automatically locking said clamping means in gripping position, the said mechanism being provided with means for releasing the same when desired.

5. In combination with a towel cabinet, means therein for holding a towel so it may be pulled from said means, a stationary element and swinging means which moves a distance proportional to the distance the towel is pulled, said swinging means being mounted to engage the towel between the same and the stationary element while the towel is being pulled from the cabinet and to automatically stop further delivery of the towel when a predetermined length of towel has been delivered from the cabinet, and mechanism for automatically locking said swinging means in gripping position, the said mechanism being provided with means for releasing the same when desired.

In witness whereof, I have hereunto set my hand this 29th day of March, 1922.

ALBERT L. OVERHOLT.
